GRANT SIPP, OF PATERSON, NEW JERSEY.

BRAKING MECHANISM FOR REELING-MACHINES.

1,119,197.

Specification of Letters Patent.

Patented Dec. 1, 1914.

Original application filed June 9, 1911, Serial No. 632,182. Divided and this application filed May 15, 1912. Serial No. 697,430.

To all whom it may concern:

Be it known that I, GRANT SIPP, a citizen of the United States, residing at Paterson, in the county of Passaic and State of New Jersey, have invented certain new and useful Improvements in Braking Mechanism for Reeling-Machines, of which the following is a specification.

This invention relates to machines for winding silk and the like on reels and it has reference particularly to the means for arresting the rotation of a reel in such a machine.

The present application is a division of my application for Letters Patent of the United States filed June 9th, 1911, Serial Number 632,182.

The principal object of the invention is to provide means for arresting the rotation of a reel which shall be effective substantially instantaneously, yet without undue incidental jar or vibration.

In the accompanying drawing, Figure 1 is a side elevation of a fragment of the machine of the character referred to provided with my invention; Fig. 2 is a front elevation of what appears in Fig. 1; and, Figs. 3 and 4 are rear and side elevations of one of the two coacting means for accomplishing the arresting of the rotation of the reel shown in Figs. 1 and 2.

a is the reel which, for the purpose of this description it is sufficient to say is journaled at one end in the frame *b* in the usual manner and at the other end is supported by a rotary member *c* with which said reel is clutched, as clearly indicated at *d* in Fig. 2. As set forth in my aforesaid application, member *c* is journaled in a bracket *e* pivoted on the axis *f* in a bracket *g* bolted to frame *b*, so that it is movable up and down, being normally supported by the driving wheel *h* with which it is in peripheral contact and which is carried by the rotary shaft *i*, suitably journaled in the frame and itself driven in any suitable manner.

The raising of the member *c* out of contact with the driving wheel *h* is accomplished as follows: *j* is a bracket secured to the frame and in which is fixed a shaft *k* affording a fulcrum for a lever comprising laterally spaced arms *l* and *m* connected by a web *n*, the web having a third arm *o* to which is bolted an upright weighted arm *p* carrying a set-screw *q* normally resting against a stop *r*.

on the frame. On shaft *k* is fulcrumed a brake-lever *s* having lateral studs *t* and *u* and the upwardly projecting portion of which is weighted at its extremity, which is rounded (Fig. 1) to form a cam and swings in a plane coincident with the member *c* (Fig. 2); in the normal position (Fig. 1) of lever *s*, where it rests against a stop *v*, being there held by the action of gravity on its weighted upper end, its cam stands close to the periphery of member *c*, so that when it moves forward against a stop *w* the cam will act to elevate said member out of contact with the driving wheel *h*. On shaft *k* is further fulcrumed a resetting lever *x* whose longer or handle arm normally rests on a stop *y*, its shorter arm extending over the stud *t* on lever *s*. Thus, when the lever comprising arms *l* and *m* is swung past the center of gravity and falls forward its arm *m* engages stud *u*, thereby swinging lever *s* past its center of gravity, lever *s* falling forward against stop *w* and incidentally effecting the elevation of member *c*, as described. When the handle end of the resetting lever *x* is raised, it engages stud *t* on lever *s*, swinging the latter back against its stop *v*, stud *u* on lever *s* engaging the lever comprising arms *l* and *m* and reestablishing it in contact with its stop *r*.

The setting in motion of the mechanism just described may be accomplished in any suitable way when the occasion therefor arises, as when the predetermined length of material has been wound on the reel; for instance, a "clock" such as is described in my Letters Patent 723,624 and which it is unnecessary to describe or show herein, may gradually move a pendulum *z* to the left in Fig. 1, ultimately releasing the same so that in its return swing under the action of gravity it will strike the broad head *l'* of the lever comprising arms *l* and *m*.

Means, now to be described, coacts with the lever *s* to clamp the member *c* and bring the rotation thereof and consequently of the reel to a stop quickly, but without undue jar or vibration. The bracket *g* has a projection 1 in which is fixed a pin 2 protruding therefrom at both its ends and forming a fulcrum for a lever 3 which is J-shaped when viewed as in Fig. 4. Projecting laterally from the lever is a toe 4 normally held against a set-screw 5 in bracket *g* by a spring 6 connecting the lever with

said bracket. Projecting laterally from the lever, oppositely to the toe 4, is an extension 7 carrying a friction-pad 8, of leather or the like, directly above and slightly spaced from the periphery of the member *c*. When member *c* is raised by the brake-lever *s* it is forced against the friction-pad of brake-lever 3, which yields slightly, resisted by the spring 6, the two levers clamping member *c* between them and bringing the same, and consequently the reel, to a substantially instantaneous stop, effected with the minimum of jar or shock owing largely to the vertical movability of said brake-levers. By adjusting the set-screw 5, the distance which the member *c* may be elevated before the co-active braking effect of the levers *s* and 3 begins may be varied at will. The brake-lever 3 may be swung back, if necessary, so as to rest against the pad 9 carried by the bracket *g*, the upper end of said lever affording a handle for this purpose.

It will be apparent that the cam-action of the lever *s* contributes materially to the quick yet, as it were, eased stopping of the rotation of the reel-driving member.

Having thus fully described my invention, what I claim as new and desire to secure by Letters Patent is:—

30 1. In combination, a rotary driving member shiftable transversely of its axis of rotation, supporting means in which said member is journaled, a brake member movable against said driving member and adapted thereupon to shift the same, and another brake member opposing the shifting movement of the rotary member and yieldable in the direction of shifting movement of said rotary member, substantially as described.

40 2. In combination, a rotary driving member, a rotary driving driven member normally held in peripheral engagement with the driving member, supporting means in which said members are journaled, a brake means movable against the driven member to shift the same away from the driving member, and brake means opposing the shifting movement of said driven member, substantially as described.

3. In combination, a rotary driving member, a rotary driving driven member normally held in peripheral engagement with the driving member, supporting means in which said members are journaled, a brake means movable against the driven member to shift the same away from the driving member, and a yielding, elastically cushioned brake means opposing the shifting movement of said driven member, substantially as described.

4. In combination, a rotary driving member shiftable transversely of its axis of rotation, supporting means in which said member is journaled, a brake member movable against said driving member and adapted thereupon to shift the same, and another elastically supported brake member opposing the shifting movement of the rotary member and yieldable in the direction of shifting movement of said rotary member, substantially as described.

5. In combination, a rotary driving member, supporting means in which said member is journaled, a brake member having a cam surface and movable to bring said cam surface against and thus shift the driving member, and another and cushioned brake opposing the shifting movement of said driving member, substantially as described.

6. The combination of the frame, a driving member journaled therein, a brake member pivoted in the frame and movable in one direction toward the driving member and in the other against the frame, and elastic controlling means for the brake member engaged on the one hand with the frame and on the other hand with the brake member at a point in the latter shiftable past a line occupied by the axis of the brake member and the point of engagement of the elastic means with the frame, substantially as described.

In testimony whereof I affix my signature in presence of two witnesses.

GRANT SIPP.
